DESIGN FOR A COMBINATION COMB AND CASE

Lester Kahn, Upper Montclair, N. J., assignor to E. I. du Pont de Nemours & Company, Wilmington, Del., a corporation of Delaware

Application August 2, 1938, Serial No. 79,029

Term of patent 3½ years

To all whom it may concern:

Be it known that I, Lester Kahn, a citizen of the United States and a resident of Upper Montclair, in the county of Essex and State of New Jersey, have invented a certain new, original, and ornamental Design for a Combination Comb and Case, of which the following is a specification, reference being had to the accompanying drawing, forming part thereof.

In the accompanying drawing:

bination comb and case embodying the design showing said comb extending from the case.

Figure 3 is a front elevational view of a combination comb and case embodying the design, showing the comb in position within the case.

I claim:

The ornamental design for a combination comb and case, substantially as shown and described.

LESTER KAHN.
